UNITED STATES PATENT OFFICE.

GEORGE L. SCHEEL, OF CHICAGO, ILLINOIS.

HAIR-DRYING COMB.

1,106,411.

Specification of Letters Patent.

Patented Aug. 11, 1914.

Application filed February 20, 1914. Serial No. 819,913.

To all whom it may concern:

Be it known that I, GEORGE L. SCHEEL, a citizen of the United States, and a resident of the city of Chicago, county of Cook, and State of Illinois, have invented certain new and useful Improvements in Hair-Drying Combs, of which the following is a specification.

My invention relates to combs and more particularly to combs adapted for use in drying hair.

The object of this improvement is to provide a simple and effective device of the character mentioned which is adapted to force warm air through the points of the teeth of the device through the hair of a person during the operation thereof.

Other objects will appear hereinafter.

The invention consists in the combinations and arrangements of parts hereinafter described and claimed.

The invention will be best understood by reference to the accompanying drawing forming a part of this specification, and in which—

Figure 1. is a longitudinal section of a comb embodying my invention; Figs. 2 and 3 are sections taken on lines 2—2 and 3—3 respectively in Fig. 1; Fig. 4 is an enlarged plan view of an insulating plug member used in the construction, and Fig. 5 is a section taken on line 5—5 in Fig. 4.

The preferred form of construction as illustrated in the drawing comprises a substantially cylindrical body 6 having one end flaring as at 7, and a rubber pumping bulb 8 engaging said flaring end. In the end of the pumping bulb 8 is a cylindrical member 9 carrying a flap valve 10 which is adapted to permit air to enter the bulb 8 through cylindrical member 9 and prevent the air from passing back through such member.

In one end of the tubular body 6 is threaded a cap 11 and provided with a recess 11' in its central inner side. Near the flaring end 7 of body 6 is formed a spider 12 having a recess 13 formed therein. The recesses 11' and 13 are in axial alinement with body 6.

50 A heating element made up of a stem 14 of insulating material and a resistance coil 15 are mounted in the hollow portion of body 6 with the ends of insulating member 14 mounted in recesses 11' and 13. The terminals of resistance wire 15 are carried through an insulating block 16 mounted in

a suitable recess in one side of hollow body 6 and secured in metallic members 17, the latter being carried by insulating plug 16. One of the members 17 carries a connecting point 18 by means of which it is connected to a source of electricity. The other of members 17 carries a knife switch member 19 adapted to engage a lever 20 which is pivoted on a contact member 21, the latter being secured on insulating plug 16. The member 21 carries a point 22 adapted to be connected with a source of electricity. The lever 20, forming the blade portion of the switch comprising members 19 and 20 carries a finger piece 23 at its outer end and by means of which it is manually operated. The points 18 and 22 are adapted to form contact members for a conventional connecting lug 24, the latter being connected by a lamp cord, not shown, or any other suitable connection with a battery 25 or any other convenient source of electricity. On one side of said hollow body 6 is a plurality of comb teeth 26; each of said teeth being provided with a perforation 27 extending longitudinally thereof from the hollow portion of body 6 to the point of the tooth, and a plurality of passages 28 leading from its perforation 27 diagonally to the sides thereof for providing a plurality of egress passages 85 for the heated air from the comb.

In operation, the connecting plug 24 is connected with the contact points 18 and 22 to connect a source of electricity with the device and the switch arm 20 moved to engagement with contact points 19 to close the circuit through the heating element. Air is then pumped through the device by manually squeezing bulb 8 to force the air contained in said bulb between the arm portions of spider 12, through body 6, contacting with the heating element comprising members 14 and 15 and through perforations 27 in the comb teeth 26. From this construction then it will be seen that air of ordinary temperatures will be received through valve 10 into bulb 8 and heated by means of the heating element and forced out through the teeth 26 into the hair of the person during operation.

In assembling the heating element in the device the terminals of the wire 15 are left sufficiently long to be inserted through the perforations in plug 16, the plug 16 inserted in its perforation in body 6 and the member 14 placed in recess 13 and the cap 11 secured

in place bringing its recess 11' into position to hold the remaining end of the member 14 thereby effecting an easy and efficient mounting for the heating element. The ends of 5 wire 15 are then drawn taut, secured in members 17 and the ends cut off substantially flush with member 17, substantially as indicated.

While I have illustrated and described the 10 preferred form of construction for carrying my invention into effect, this is capable of variation and modification without departing from the spirit of the invention. I, therefore, do not wish to be limited to the 15 precise details of construction set forth, but desire to avail myself of such variations and modifications as come within the scope of the appended claims.

Having described my invention what I 20 claim as new and desire to secure by Letters Patent is:

1. A device of the kind described comprising a comb having a hollow body with both ends thereof open; a spider in said 25 body near one end thereof and having a recess therein; a cap provided with a recess therein and fitted in the other end of said body; and a heating element disposed in said hollow body and supported in said recesses, substantially as described.

2. A device of the kind described comprising a comb having a hollow body with both ends thereof open; a spider in said 30

body near one end thereof and having a recess therein; a cap provided with a recess 35 therein and fitted in the other end of said body; a heating element disposed in said hollow body and supported in said recesses; and air pumping means connected with one end of said hollow body and adapted to 40 force air over said heating element, substantially as described.

3. A device of the kind described comprising a comb having a hollow body with one end of said body open; a spider in said body 45 having a recess opening toward the open end of said body; a cap threaded in said body, there being a recess in said cap opening toward said spider; and a heating element in said body with its ends mounted in said recesses, substantially as described.

4. A device of the kind described comprising a comb having a hollow body with a lateral opening therein; an insulating plug in said opening; a wire electrical heating 55 coil in said body with its ends thereof extending through said plug; and means on the outer side of said plug locking the ends of said wire, substantially as described.

In testimony whereof I have signed my 60 name to this specification in the presence of two subscribing witnesses.

GEORGE L. SCHEEL.
